B. J. J. GOULDING

ROTARY WEB OFFSET PRINTING MACHINE

Original Filed June 30, 1924

UNITED STATES PATENT OFFICE.

BENJAMIN JOSEPH JOHN GOULDING, OF LONDON, ENGLAND, ASSIGNOR TO LINOTYPE AND MACHINERY LIMITED, OF LONDON, ENGLAND, A BRITISH COMPANY.

ROTARY WEB OFFSET PRINTING MACHINE.

Original application filed June 30, 1924, Serial No. 723,084, and in Great Britain July 12, 1923. Divided and this application filed July 8, 1925. Serial No. 42,230.

This invention relates to rotary web offset printing machines and has for its object to provide a new or improved construction whereby adjustments of a transfer cylinder relatively to the co-operating forme cylinder and companion transfer cylinder can be readily effected without shifting of the forme cylinder.

The invention comprises a transfer cylinder so arranged as to be adjustable relatively to the respective forme cylinder both about the axis of the last named cylinder and towards and away from that axis.

The invention is applicable to machines for perfecting printing by either offset on both sides of a web, or offset on one side and direct printing on the other side, or for single side printing by offset.

The invention will now be described by reference to the accompanying drawings in which:—

Figure 1 is a side elevation of one constructional form adapted for offset printing on both sides of the web, only such parts of the machine being represented as are considered pertinent; and

Figure 2 is a plan of a part of Figure 1.

In the constructional form represented in the drawings there are provided two forme cylinders 1, the shafts or trunnions 2 of which rotate about stationary axes in the two side frames 3 of the machine; of these two side frames only that on the near, or so-called plain, side of the machine is represented. 5 represent the two transfer cylinders constituting a printing couple and the shafts 13 of which are journaled in eccentric bushes 14 angularly adjustable in the respective side frames 3, each of said bushes, for this last-named purpose, being provided with an outstanding arm 7 to which is pivoted the upper end of a link 6 provided with a turnbuckle 6^a which latter permits of the effective length of said link being varied. 40 The lower end of the links 6 are connected to suitable lever and link or equivalent mechanism by which they can be operated conjointly or individually.

The eccentric bushes 14 are each angularly adjustable within an outer eccentric bush 38, their angular disposition relatively to the bushes 38 and companion forme cylinder being such that when so adjusted they serve to move the respective transfer cylinder 12 to-

wards and away from the said forme cylinder 1, while the adjustment of the outer eccentric bushes 38 angularly about the bushes 14 serves to move the same transfer cylinder bodily about the axis of the last-named forme cylinder.

For effecting the just-named adjustment of the outer bush 38, the flange of this latter is formed with a segmental toothed rack 39 with which engages a toothed sector 40 integral with a hand lever 41 which is capable of being turned on a pivot 42 fast to the respective side frame 3. The just-mentioned flange is further provided with arcual slots 43 traversed by clamping bolts 44 threaded, in the example illustrated, into the bearing cap 45, these bolts being loosened only when it is desired to adjust the outer bush 38.

The turnbuckles 6^a are provided with lock nuts 8, by which they can be secured in any position of adjustment.

It has heretofore been suggested to employ two angularly adjustable eccentric bushes one within the other, for moving a forme cylinder relatively to an impression surface, but these were proposed both for moving the forme cylinder outward from, and inward towards the impression surface and one for regulating the printing pressure and the other for tripping, as when a sheet is missed. This arrangement differs from that according to the present invention in so far as the two "nested" bushes of the latter are so angularly related to each other and to the co-operating surfaces, the pressure between which is to be adjusted, that angular movement of one bush serves to move the adjustable cylinder about the axis of the forme cylinder while angular movement of the other bush serves as heretofore to move one cylinder towards or away from the co-operating printing element.

Having described my invention, I declare that what I claim and desire to secure by Letters Patent is:—

In a rotary web offset printing machine, 100 the combination with the machine frame and two forme cylinders rotating about stationary axes therein, and two transfer cylinders constituting a printing couple and each contacting with one of the forme cylinders and a fixed bearing in the frame for each of the transfer cylinders, of an eccentric bush angularly adjustable in the fixed bearing, a 105

toothed sector operatively engaging the bush for effecting said angular adjustment, locking means securing said bush in adjusted position, a second eccentric bush angularly adjustable within the first-named one and having the shaft of the transfer cylinder rotatable within it, and lever and link de-

10 vices operatively engaging the second eccentric bush for effecting its angular adjustment.

In testimony whereof I have affixed my signature hereto.

BENJAMIN JOSEPH JOHN GOULDING.
